CAR DOOR

Filed Sept. 2, 1922

Inventor

WILLIAM E. WINE,

By

R. W. Kadel.

Attorney

UNITED STATES PATENT OFFICE.

WILLIAM E. WINE, OF TOLEDO, OHIO.

CAR DOOR.

Application filed September 2, 1922. Serial No. 585,968.

To all whom it may concern:

Be it known that I, WILLIAM E. WINE, a citizen of the United States, residing at Toledo, in the county of Lucas and State of Ohio, have invented certain new and useful Improvements in Car Doors, of which the following is a specification.

This invention relates to a door for railway cars or the like, and has among its objects to provide an improved form of door which will be relatively strong and economical of construction. Another object is to provide a door having formed therein a stiffening arrangement, and also a door having sealing means formed therein. Other objects are to provide a door of economical construction and improved arrangement of hinges and of door supporting members.

With such objects in view, the invention consists of the formation, combination and arrangement of parts as will be herein described and particularly as pointed out in the appended claims.

In the accompanying drawings, which show a preferred form of the invention, Figure 1 is a vertical longitudinal section through the hopper portion of a car of the ordinary twin hopper type, having applied thereto a door constructed in accordance with the principles of the present invention. It will be understood that the door is applicable to any type of car and may be formed in a variety of styles. The twin hopper type of car, as selected, is convenient for a showing of the invention. Figure 2 is a view of the outermost face of the door, as shown in Figure 1, this view showing the door hinges and door-supporting beam secured thereto. In doors of the type selected for showing in the present embodiment, it will be understood that a pair of doors is usually supplied and these are connected by means of the door spreader. In the present drawings, but one door is shown and the door spreader is shown as broken, but it will be understood that in such an embodiment a similar door is provided for the hopper at the opposite side of the car and the door spreader will serve in the usual manner to connect the doors.

Referring to these drawings, the hopper side of the car is indicated at 1, and at 2 is indicated the hopper floor plate or chute plate. A transverse connecting plate is indicated at 3, and to this is shown a body hinge 4, which is secured to the car body as by

means of the rivet 5. Such construction is well known in the art.

The door 6 is adapted to close the opening of the chute, this opening being defined by the margins of the side plates, such as 1, and the floor plate, such as 2, also by the lowermost extremity of the cross plate, such as 3. Formed entirely around the margins of the door and slightly removed from the edges of the door, there is a continuous corrugation 7. This corrugation is adapted to stiffen the door plate, and also to form a sealing means. The general plane of the door plate is disposed against the face of the hopper discharge opening, and the corrugation 7 extends inwardly of this opening, so that it effectively seals the opening by constituting an inturned flange for the entire periphery of the opening. The flat portions 8 of the door plate, which lie outside of the lines of the corrugation 7, preferably lie in the same plane as that of the general plane of the door plate, and these edges constitute flanges which abut directly against the edges of the plates, which define the hopper discharge opening.

The door spreader 9 may be of the customary type formed of a channel member and this, with a door constructed with the principles of the present invention, may extend continuously across the outer face of the door without interruption as is the case where corrugations are formed outwardly of the door plate, or where marginal flanges are outstanding from the door plate. The door spreader is secured to the door as by means of rivets 10, and it will be noted that some of these rivets are disposed at either side of those portions of the corrugation 7 over which the door spreader passes. This attaches the flanged portions 8 of the door to the central portion of the door plate and forms a reinforcement across the corrugation. This is of special importance near the outer edges of the door, as the door is often held in closed position by door-supporting means such as the hook 11, which is arranged to engage a suitable member on the door, or on the door spreader near the outer edge of the door. The hook 11 in the present embodiment is shown as pivoted to the hopper side 1 at 12, and may be swung about the pivot 12 into or out of engagement with the angle iron 13, which is secured to the door spreader for this purpose. Rivets 14 and 15 may also extend through the one leg of this

angle iron and through the door plate, the rivet 14 being located outside of the corrugation 7, and the rivet 15 inside of the corrugation 7, thus constituting an additional tie across the corrugation in this vicinity. The other leg of the angle 13 may be secured to the web of the channel spreader 9 by means of rivets 16. The door hinges 17 are shown as attached to the outer face of the door 10 and these extend from the top of the door down to the vicinity of the door spreader 9. They may be secured to the door by means of rivets 18, and it will also be noted that one of the rivets 18 for each 15 of the hinges lies above the corrugation 7, and others thereof lie below this corrugation, thereby forming a tie across the corrugation to transmit the vertical forces. The rivet 15, which passes through the angle iron 13 20 and through the door plate, may also pass through the lowermost end of one of the door hinges, thus securing all the parts together.

Doors constructed in accordance with the 25 principles of this invention will in general conform to the shape of the discharge opening and the corrugation will extend around the periphery of the door plate following the line of the discharge opening, as shown 30 in the present embodiment. The corrugated portion of the plate will in general fall inside of the plane of the discharge opening, as heretofore explained. The door may be formed of a single sheet of metal and the 35 usual appurtenances, such as the hinges and the door spreader, may be applied thereto in a manner to provide such stiffeners as are desirable for use with the peripheral corrugations.

40 I have thus described an embodiment of my invention. Other embodiments are contemplated within the scope of the appended claims without departing from the spirit thereof.

45 What is claimed is:

1. A door for the discharge opening of a railway car, the same being formed of a plate of metal conforming in general shape to the outline of the discharge opening, a 50 corrugation formed around the periphery of the door plate, the same following the lines of the discharge opening, the general plane of the door plate being arranged when closed, to coincide substantially with the 55 face of the discharge opening, the corrugated portion of the same extending inside of the plane defining the face of the discharge opening in a manner to constitute therewith a sealing means.

60 2. A door for the discharge opening of a railway car, the same embodying a plate of sheet metal arranged to lie, in closed position, in the plane defining the face of the dis-

charge opening, a peripheral corrugation formed around the plate, the same substantially defining the inner edges of the discharge opening and extending inwardly of the face of the discharge opening and of the general plane of the door plate and arranged to provide, in conjunction with the walls of the discharge opening, a sealing means. 65

3. A door for the discharge opening of a railway car, the same embodying a plate of sheet metal arranged to lie, in closed position, in the plane defining the face of the 70 discharge opening, a stiffening corrugation formed around the plate, the same substantially defining the edges of the discharge opening and being pressed from the plate wholly toward the lading side of the door 75 and extending inwardly of the face of the discharge opening and of the general plane of the door plate, and hinge members secured to the outer face of the door plate, the same passing uninterruptedly over the back 80 of the said corrugation.

4. A door for the discharge opening of a railway car, the same embodying a plate of sheet metal arranged to lie in closed position in the plane defining the face of the 85 discharge opening, a stiffening corrugation formed around the plate, the same substantially defining the edges of the discharge opening and extending inwardly of the face of the discharge opening and of the general 90 plane of the door plate, and hinge members and door supporting member secured to the outer face of the door plate, the same passing uninterruptedly over the back of the 95 said corrugation and means securing the said hinge members and door supporting member to the door plate on each side of the 100 said corrugation wherever said members cross the said corrugation.

5. A door for the discharge opening of a railway car, the same embodying a plate of sheet metal arranged to lie in closed position in the plane defining the face of the discharge opening, a stiffening corrugation formed around the plate, the same substantially defining the edges of the discharge opening and being pressed from the plate 105 wholly toward the lading side of the door and extending inwardly of the face of the discharge opening and of the general plane 110 of the door plate, and door supporting members secured to the outer face of the door plate the same passing uninterruptedly over the back of the 115 said corrugation and means securing the said door supporting members to the door plate on each side of the corrugation wherever said supporting members cross the said corrugation. 120

In testimony whereof I affix my signature.

WILLIAM E. WINE.
